US0D1050712S

(12) United States Design Patent (10) Patent No.: US D1,050,712 S
(45) Date of Patent: * Nov. 12, 2024

(54) ARTICLE HOLDER

(71) Applicant: WanderFull, Corp, Westport, CT (US)

(72) Inventors: Lisa Raphaeli Watkins, Westport, CT (US); Kathryn Hoffman Hill, Westport, CT (US)

(73) Assignee: WanderFull, Corp, Westport, CT (US)

() Term: 15 Years

(21) Appl. No.: 29/861,720

(22) Filed: Dec. 1, 2022

(51) LOC (14) Cl. 09-02

(52) U.S. Cl.

USPC D3/202; D3/287

(58) Field of Classification Search

USPC D3/201, 202, 203.1, 205, 215–217, 221, D3/226–233, 234, 238, 244–246, 254, D3/255, 269, 270, 271.1, 273–277, D3/289–292, 294, 299, 301–304, 306, D3/315, 316, 318, 319, 901, 904, 905, D3/287; D7/601, 607; D9/702, 703, D9/705–707; D12/423, 425; D24/169; D30/108, 199

(57) CLAIM

The ornamental design for an article holder as shown and described.

DESCRIPTION

FIG. 1 is a perspective view of an article holder showing the new design;

FIG. 2 is a front plan view thereof;

FIG. 3 is a rear plan view of thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines on the surface of the article holder illustrate claimed stitching. The remaining broken lines illustrate portions of the article holder that form no part of the claimed design.

1 Claim, 7 Drawing Sheets
